ELECTRICALLY DRIVEN VACUUM CLEANER

John James Hambidge, London, England

Application February 7, 1931, Serial No. 514,275,
and in Great Britain March 28, 1930

1 Claim. (Cl. 15—16)

This invention relates to electrically driven vacuum cleaning machines and has particular reference to the domestic type of machine comprising an electric motor driven suction fan provided with dust collecting or cleansing nozzles and a dust filter bag, the whole being assembled as a mobile push-about device.

The object of the present invention is to provide an improved and simplified machine of the kind above indicated which is so constructed as to be applicable, without the use of flexible hose, not only for cleaning floors, carpets or the like but for cleaning curtains, cornices, friezes, chairs and other articles and places which are ordinarily inaccessible to a wheeled vacuum cleaning machine.

According to one form, the present invention consists in an electrically driven vacuum cleaning machine of the wheeled type comprising an electric motor and a suction fan co-axially mounted and constituting a machine capable of use for cleaning floors, carpets or the like or for cleaning curtains, furniture and other articles and places not ordinarily accessible to a vacuum cleaning machine without the use of flexible hose.

According to another form of the invention an electrically driven vacuum cleaning machine comprises an electric motor mounted in axial alignment with a suction fan and a handle hinged to the fan casing but adapted to be fixed relatively thereto at will to change the machine from a floor or carpet cleaner to a portable cleaner for walls, curtains, furniture or the like without the use of flexible hose.

Reference will now be made to the accompanying drawings which illustrate by way of example a construction according to the invention and in which:—

Fig. 1 is an elevation of a vacuum cleaning machine constructed in accordance with the invention, showing the handle in the unlocked position occupied for floor cleaning.

Fig. 2 is a fragmentary elevation of the said vacuum cleaning machine on an enlarged scale showing the handle in the locked position.

Fig. 3 is a plan of the machine shown in Fig. 2.

Fig. 4 is a front elevational detail of the means for locking the cleaning nozzle in position, and

Fig. 5 is a view in elevation of an extension piece for the suction tool.

In the construction illustrated, an electric motor *a* is mounted vertically above a suction fan *b* which is disposed in a casing *c* lying in a horizontal plane and carrying at its forward end a suction nozzle coupling *d* and carrying at the rear of

one side, a dust and air discharge passage or duct *e*. The suction fan motor and accessory parts are made as light as possible to which end the electric motor is of the high speed type and is mounted vertically with the suction fan *b* directly 60 mounted upon an extension *s* of the motor spindle, as shown in Fig. 5.

To the rear of the fan casing *c* is disposed a pair of brackets *f* to the lower ends of which a pair of wheels *g* is mounted to support the machine from the floor. The brackets also serve together as a support for a short lifting handle *h* which is pivoted as at *h'* to the brackets and has a spring catch *i* adapted to engage a slot *j* in one of the brackets *f* so that the handle *h* may 65 be locked rigidly with the fan casing, when required as hereinafter described. The spring catch *i* is so arranged relatively to the handle *h* that it can be readily operated by the thumb of the operator its outer end *k* being depressible 70 against the action of a leaf spring *l*.

The short handle *h* is formed at its outer extremity to engage with a socket *m* formed on a handle extension *n*, a wing nut set screw *o* being 75 employed for readily connecting the two handle 80 sections together by tightening the metal band which constitutes the socket *m*. The electric motor *a* is preferably formed with a ventilated outer insulating cover and is of the universal voltage type the electrical connections to the 85 motor as by a cord *s* being by way of a flexible lead *p* which passes through insulating collars *q* on the short handle *h*. The longer portion of the handle *n* is provided with cleats *r* about which the flexible cord *s* is wound when the device is 90 not in use. The short handle *h* also carries a single pole switch *t* on its under side which is capable of operation by the finger of the operator when the short handle above is used and by the 95 foot when the longer handle is employed.

The detachable dust filter bag *u* which is preferably made with a double thickness of fabric material is preferably impregnated with disinfectant. Its forward end is provided with means for detachably engaging the discharge duct or passage *e* of the fan casing and its rear end is closed by a grooved metallic clip *v* to which one end of a tension spring *w* is attached its opposite end being anchored to the long handle *n* (see Fig. 1).

For operation with the short handle only, the dust filter bag has an external loop *x* formed transversely across it through which the operator can place the arm of the hand which grasps 100 the short handle. The cleansing tools are rigidly 105 110

and removably connected with the suction nozzle *d* by means of an internally flanged sleeve *y* which has two inclined slots *z* engaging fixed pins 2 on the nozzle *d* and is recessed at 3 at its 5 forward edge to permit the passage of two lugs 4 formed on the operating tool 5 which engage corresponding recesses 6 in the suction fan inlet *d* thereby locking the tool against rotation and preventing accidental displacement when the 10 flanged sleeve *y* is rotated after the tool has been mounted in operative position. One of the pins 2 on which the flanged sleeve *y* is partially rotatable may be a screw threaded element provided with an operating knob 7 to enable the 15 sleeve to be locked in adjusted position and prevent detachment of the cleaning tool 11 during use. A rigid distance tube may be employed as an extension piece for the suction tool, said extension piece having at one extremity coupling 20 elements whereby it may be coupled with the flanged sleeve *y* in the manner in which a tool may be attached to said sleeve, as described above, and having at its other extremity a flanged sleeve 12 whereby the various tools may 25 be attached thereto.

In operation and using the short handle *h*, the nozzle, suction fan and motor are made rigid with the handle *h* by causing the catch *i* to engage in the recess *j* and as the weight of the 30 suction fan and motor are positioned so as to give the best possible leverage, the operator can lift the device with comfort whilst having one free hand for presenting curtains or other articles to be cleansed to the influence of the suction nozzle. During this operation the operator 35 partially supports the filter bag on the arm since the arm supporting the device may pass through loop *x*. If ceiling decorations, picture rails and like articles of household decoration normally 40 inaccessible require cleansing, then the handle extension *n* is fixed to the short handle *h* and the latter is still maintained rigid with the machine. Should the device be required for carpet 45 or floor cleaning then the machine is placed on the floor in such manner as to run on its wheels and is supported in front by the cleaning nozzle as shown in Fig. 1, the longer handle being attached to the shorter one which is released from 50 its locked position when the machine is to be used for this purpose.

As shown in Fig. 2, the forward portion of the 55 cord *s*, by which the motor *a* is connected to a source of current, is mounted in the short front section *h* of the handle, and enters said section forwardly of but close to the rear end of the latter, and the switch *t* for closing the electric circuit through the cord *s* is carried by the lower 60 side of said section adjacent the forward end of said section. After the removal of the long rear handle section *n* from the front handle section *h*, and after the front handle section *h* has been

secured by the catch *i* rigidly to the motor *a* and fan casing *c*, the cleaner may be conveniently held in one hand when cleaning furniture, draperies or the like. When the cleaner is so used, the front handle section *h* extends rearwardly 80 from the motor *a* and the fan casing *c* at substantially a right angle to the axes of the motor and fan, and the handle section *h* is grasped by a hand of the user between the switch *t* and the point at which the cord *s* enters the handle section. Since the cord *s* extends through the handle section *h*, and since this handle section is grasped forwardly of the point at which the cord enters the same, the cord will not interfere with the manipulation of the cleaner. Inasmuch as 85 the switch *t* is located at the lower side of the forward end of the handle section *h*, it may be conveniently actuated by the fingers of the hand which grasps said handle section. When the long rear handle section *n* is to be used, the catch *i* is retracted to permit the handle section *h* to rock on its pivot *h'*, and the switch *t* may be 90 conveniently actuated by a foot of the user.

I claim:

In an electrically driven vacuum cleaning machine, a horizontally disposed suction fan casing, a motor mounted upon the casing with its axis extending vertically, wheels journaled on the fan casing, a handle including detachably connected front and rear sections, the front section of the handle being short and pivotally connected at its front end to the rear side of the fan casing, a cord mounted in the front section of the handle and having its front end connected to the motor, the rear end of said cord extending from a side of the front section of the handle for connection with a source of current and at a point adjacent the rear end of said front section, a switch in the cord carried by the rear side of the front section of the handle and at a 100 point adjacent the front end of said front section, the extension of the cord from a side of the front section of the handle and the mounting of the switch on said section adapting the machine to be used with or without the rear section of the handle, the location of the switch at the rear side of the front section of the handle adapting the switch to be operated by the foot when the rear section of the handle is used and adapting it to be operated by the hand when the front section of the handle is used, and means 105 adapted to lock the front section of the handle to the fan casing with said section extending rearwardly from the fan casing at substantially right angles to the axis of the fan casing and motor, whereby to adapt the machine to be held in the hand by the short section of the handle and with the fan casing and motor in front of 110 said section.

JOHN JAMES HAMBIDGE. 135
